CONDENSER

Francis X. Govers, Vincennes, Ind., assignor to
 Indian Refining Company, Lawrenceville, Ill., a
 corporation of Maine

Application April 20, 1931, Serial No. 531,598

3 Claims. (Cl. 257—34)

The present invention relates to a condenser and means for mounting the same.

In the use of condensers for the condensation of vapors which have wide boiling point ranges it is necessary that such condensers shall be free to expand in all directions. It is also most advantageous that such condensers be provided with means permitting the cleaning of the water cooled tubes while in operation, that free passage be allowed for the vapors, and that the condenser surfaces be as close as possible to the surface of the liquid being evaporated. This last feature is of particular importance when it is desired to maintain the back pressure or tension on the liquid as low as possible, as in high-vacuum distillation.

The foregoing characteristics are provided in the condenser of my invention which has been designed particularly for use in the distillation of the lubricating fractions of mineral oils under low absolute pressure.

The condenser and mounting will now be described in connection with the accompanying drawings in which:

Fig. 1 shows the condenser mounted in the head of a still;

Fig. 2 is an enlarged view, partly in section and partly in front elevation of the condenser;

Fig. 3 is an enlarged broken section of the expandable joint in the cooling water supply line; and

Fig. 4 is an enlarged broken section of the bottom of the condenser.

Referring to Fig. 1, the condenser A is supported in the head of the still B by means of the flanges 1 and 2. The condensing surface, i. e., the bank of tubes 3, extends beyond the outer shell 4 of the condenser and into the body of the still, thereby providing a relatively short path for the movement of the vapors from the body of liquid being evaporated in the still into contact with the condenser surface and ample open space is provided between the shell 4, the wall 5 of the still and the lower tube sheet 6, for the free passage of the vapors from the still into contact with the tubes.

A basin 7 and drain pipe 8 both provided with heat insulation 9 may serve to catch and discharge the condensate flowing off of the tubes. The condenser might be used for refluxing by omitting the basin 7.

Referring to Fig. 2 the condenser comprises the cylindrical shell 4 provided at its upper end with the bustle pipe 10 and outlet pipes 11, 11 for uncondensed gases. Pipes 11, 11 may com-

municate with an ejector or other suitable means for producing sub-atmospheric pressure in the condenser. The upper end of the shell 4 carries the tube sheet 12 from which the nest of tubes 3 is suspended. The lower tube sheet 6 carries the skirt or short shell 14, the bottom open-end of which is closed by the plate 15 bolted to the flange 16. The flange 16 is secured to the shell 14 by welding at 17. A packing 18 serves to provide a tight joint between the flange 16 and the plate 15. The tube sheets 12 and 6 are provided with central openings into which are secured in any suitable manner as by welding the tubes 19 and 20 to be described more fully hereafter. Mounted on the tube sheet 12 is a cooling water discharge device comprising the outer shell 21, the inner shell 22 of less height than shell 21, the discharge pipe 23 and cover plate 24 provided with a central opening for the pipe 19. The pipe 19 is secured into and extends upwardly from the central opening in the tube sheet 12, and the pipe 20 extends downwardly through the pipe 19, sufficient clearance for free relative movement being provided, and through the opening in the tube sheet 6 into the chamber 25 formed by the tube sheet 6 the shell 14 and the plate 15. The discharge end of pipe 20 is so positioned with respect to plate 15 as to provide an equitable distribution of the cooling water to the tubes 3. A fluid-tight flexible joint between pipes 19 and 20 is provided by the expandable joint C.

In operation of the condenser cooling water is supplied through the pipe 20 to the chamber 25 from which it flows upwardly through tubes 3 over the top of the shell 22 and out through the discharge pipe 23. Vapors generated in the still B pass upwardly freely into contact with the tubes 3 and condensate flows downwardly into the basin 7 and out by way of the pipe 8 while uncondensed vapors or gases are discharged from the condenser by way of pipes 11. As will be apparent the vapors passing from the still to the condenser are not forced to pass through a down flowing curtain of condensate and entrainment is thereby largely avoided. It is further apparent that the cover 24 may be removed and the tubes 3 cleaned without interrupting the operation of the condenser. Due to the construction of the condenser and the manner in which the parts are supported, as described above, expansion and contraction due to changes in temperature may occur without breaking the necessary fluid-tight joints. It may be noted that in the use of the condenser it may be necessary to connect pipes 11, 11 and 23 to an associated apparatus (not

110

shown), such as, for instance, a conduit for conveying water from pipe 23 to waste and conduits providing communication between the pipes 11, 11 and a vacuum producing device through flexible couplings.

Obviously many modifications and variations of the invention, as hereinbefore set forth, may be made without departing from the spirit and scope thereof, and therefore only such limitations should be imposed as are indicated in the appended claims.

I claim:

1. A condenser structure comprising an outer shell, an upper tube sheet extending across and attached thereto, a nest of tubes extending into and suspended from said upper tube sheet, a second tube sheet attached to the lower ends of said tubes open-spaced from the outer shell, a flanged shell attached to said second tube sheet, a removable cover attached to said flange, a central supply pipe attached to and extending through said second tube sheet, a tube concentric with said central supply pipe and extending up from and attached to said upper tube sheet and an expandible joint between the central supply pipe and said tube.

2. A condenser structure comprising an outer cylindrical shell, an upper tube sheet extending across and attached to said shell, a nest of tubes depending from said tube sheet and extending beyond said shell, a second tube sheet attached to the lower end of said nest of tubes, walls defining

a chamber below said second tube sheet and communicating with said nest of tubes, a pipe attached to and extending upwardly from an opening in said upper tube sheet, a second pipe extending downwardly through said first named pipe and through said second tube sheet into said chamber and attached to said second tube sheet, an expandible joint connecting said pipes at a point above said upper tube sheet, and walls open-spaced from said lower tube sheet defining a chamber communicating with the lower end of said shell.

3. A condenser structure comprising an outer cylindrical shell, an upper tube sheet extending across and attached to said shell, a nest of tubes depending from said tube sheet and extending beyond said shell, a second tube sheet attached to the lower end of said nest of tubes, walls defining a chamber below said second tube sheet, and communicating with said nest of tubes, a pipe attached to and extending upwardly from an opening in said upper tube sheet, a second pipe extending downwardly through said first named pipe and through said second tube sheet into said chamber and attached to said second tube sheet, an expandible joint connecting said pipes at a point above said upper tube sheet, walls open-spaced from said lower tube sheet defining a chamber communicating with the lower end of said shell and means in said last named chamber for collecting condensate.
